DESIGN FOR A BUTTER CUTTER

Harold E. Cocke, Oakland, Calif.

Application February 11, 1946, Serial No. 126,439

Term of patent 3½ years

(Cl. D23—1)

To all whom it may concern:

Be it known that I, Harold E. Cocke, a citizen of the United States, residing at 174 41st Street, Oakland, in the county of Alameda and State of California, have invented a new, original, and ornamental Design for Butter Cutters, of which the following is a specification, reference being had to the accompanying drawing, forming part thereof.

In the drawing:

Fig. 1 is a front perspective view of a butter cutter, showing my new design;

Fig. 2 is a rear perspective view showing same as it appears in open position;

Fig. 3 is another rear perspective view showing the butter cutter in closed position.

Fig. 4 is an end elevation, Fig. 5 is a front elevation and Fig. 6 is a bottom plan view.

I claim:

The ornamental design for a butter cutter, as shown.

HAROLD E. COCKE.
